UNITED STATES PATENT OFFICE.

ABRAM REESE, OF PITTSBURG, PENNSYLVANIA.

UNIVERSAL ROLLING-MILL.

SPECIFICATION forming part of Letters Patent No. 481,058, dated August 16, 1892.

Application filed November 25, 1891. Serial No. 413,151. (No model.)

To all whom it may concern:

Be it known that I, ABRAM REESE, a citizen of the United States, residing at Pittsburg, in the county of Allegheny and State of Pennsylvania, have invented certain new and useful Improvements in Universal Rolling-Mills; and I do hereby declare the following to be a full, clear, and exact description of the invention, reference being had to the accompanying drawings, which form part of this specification.

My invention has relation to rolling-mills for rolling iron and steel **I**-beams and channel-bars, and has for its object the provision of novel means for rolling such beams more accurately, rapidly, and economically than by any of the methods or appliances heretofore employed.

In rolling **I**-beams and channel-bars grooved rolls are now employed, the different reducing and finishing passes being made through separate grooves of graduated gage and shape, the mills being of the ordinary construction and conformable to the ordinary type of rolling-mill, the form and relation of the grooves being their only distinguishing feature.

In rolling **I**-beams for girders and general building purposes the ingots are very large and the rolls are subject to very great strain in consequence of the power and pressure required in reducing the web of the ingot and causing the flanges to fill the grooves in both rolls. Many passes are necessary in rolling and finishing a beam of ordinary size and much time, labor, and expense entailed.

Grooved rolls are in themselves costly and are subject to very rapid wear, necessitating frequent returning and recutting, and adjustment is practically restricted to exact limits, these being entirely inadequate to the demands of the work to be done. Under the most favorable conditions, however, it is impossible to roll **I**-beams of accurate form and structure by means of grooved rolls, and the principal difficulty is in rolling the flanges so as to produce and preserve the proper depth, surface, and angle and avoid irregularity and lack of fullness and finish on the edges and sides. The filling of the grooves of the rolls is dependent upon the pressure of the body of the roll between the grooves, the metal of the beam-ingot being forced out from the web

toward the flanges and into the grooves the sides of which aid little, if at all, in the rolling and reducing action, their purpose and effect being simply to limit the spread of the metal. The sides of the grooves are not only ineffective as reducing agencies, but are, in fact, obstacles and drags, opposing the free movement of the ingot and tending to hoist and tear the surfaces in which they are in rubbing but not in free rolling contact, impeding the uniform longitudinal stretch of the metal, as well as its lateral spread, and preventing in a great measure the complete filling of the grooves of both upper and lower rolls.

My present invention aims at entirely overcoming the difficulties above referred to, as well as many others met with in rolling flanged beams, and to this end contemplates the rolling of **I**-beams and channel-bars in and by a system of rolls constituting a universal mill, in which grooved rolls are entirely discarded and the obstacles to the production of a flanged beam of any standard size and of accurate form and finish entirely eliminated, and by the mill embodying my invention and the method of operating the same I claim to be able to produce such beams with less labor, more rapidly, and at less cost than now incurred in the production of imperfect beams.

My invention consists in the novel construction, combination, and arrangement of parts hereinafter described and claimed.

In the accompanying drawings, Figure 1 is a vertical longitudinal section on the line *xx* of Fig. 3. Fig. 2 is a horizontal sectional view on the line *yy* of Fig. 1. Fig. 3 is a transverse vertical section on the line *zz* of Fig. 1. Fig. 4 is an end elevation. Figs. 5, 6, 7, and 9 are detail views of the vertical rolls of the second pass with their bearing-blocks and adjusting devices. Fig. 8 is an end view of the sliding yoke for adjusting the vertical rolls of the first pass. Fig. 10 is a detail elevation of a modified form of adjusting devices for the vertical rolls of the first pass, and Fig. 11 is a vertical sectional view of a part of the devices shown in Fig. 10.

The mill is of a compound or double character and consists of two separate or distinct sets of rolling appliances for the operation of two separate and independent passes.

A A and B B designate the housings, respectively, of the two roll structures, and C C' D D' the horizontal rolls mounted therein. The rolls C C' are employed in the first pass to which the ingot is subjected and, in connection with the vertical rolls c c c' c', mounted on the same housing, are designed to roll and reduce the web of the I-beam and at the same to operate positively on the flanges of the beam, so as to determine the exact width and depth of the latter between the flanges and the proper corresponding depth of the flanges. For rolling I-beams the rolls C C', which are of the same size and structure and which in practice are to be of such weight and dimension as may be required, are formed each with a central enlargement, body part, or collar C² upon or raised from the neck portions c² of the exact width and shape as the space or channel between the flanges on one side of the beam can be produced. To make a channel-bar, a plain roll is used as the top roll.

The lower roll C' is mounted in stationary boxes E E, while the upper roll C is mounted in adjustable boxes E' E' of the usual construction and arrangement, suitable adjusting-screws E² E², rising above the housings and carrying hand or power wheels E³ E³, being provided and the boxes supported on springs E⁴ E⁴ or balanced in any convenient way.

The collars C² are rounded on their angles, as shown at e, to correspond with the curve of the inner sides of the flanges of the beams, and between the periphery of the collars C² and the body of the rolls the distance is exactly that of the projecting of the flanges from the surface of the web of the beam.

The vertical rolls c c c' c', which operate in connection with the main horizontal rolls C C', are located, respectively, in front of and behind the rolls C C' and for the purposes of the lateral adjustment, which is a necessary function of these vertical rolls, they are mounted or journaled in grooved brasses or boxes f f, fitted to the edges of slots f' f' in transverse bars f² f², attached to the housings A A in the usual manner.

The rolls c c c' c' are driven from the shafts d d' by means of the beveled pinions d² d³, the former being keyed to the spindles of the rolls and the latter provided with grooved collars d⁴ and adjustably splined upon their shafts, so as to adjust with the rolls c c c' c', the lower spindles d⁵ of which engage with the grooves in the collars d⁴.

The rolls c c c' c' are fed or adjusted inwardly toward the collar C² by means of the double wedge-shaped vertical slides G G, which play in boxes G' G' on the inner faces of the housings A A and pass through the slots f' f' in the bars f² f² behind the boxes or brasses f f, in which the vertical rolls c c c' c' have their bearings, the inclined faces g³ of the wedges being outward or toward the boxes, so as to impinge against the latter and force them inward, according as the wedges are

lowered. The sides of the boxes or brasses f f are beveled to correspond with the bevel or taper of the wedges, as shown at f³ f³, so that the contacting-surfaces shall be in easy sliding touch.

In order to take up and compensate for wear due to the friction of the wedges, I provide the device shown in Figs. 10 and 11, in which H is a grooved and beveled block sliding in the slot f' between the roller-bearing f and the wedge-slide G, and carrying an upright threaded pin h, upon which is fitted the horizontal arm of an L-shaped adjusting-key h', the beveled limb h² of which fits between the vertical side of the block H and the beveled side of the bearing f. Nuts i i are screwed upon the pin h, above and below the horizontal arm of key h', and provide a means for adjusting the key h', so as to move the block H toward the wedge, according as the contact-surfaces wear.

The wedges or wedge-slides G are operated through the medium of the horizontal shafts I I', journaled on the housings A A above the rolls c c c' c' and carrying the pinions i² i² i³ i³, engaging with the racks i⁴, formed on the sides of the wedge-slides. On one end of the shaft I is secured a crank-arm I², by which it is turned. This shaft carries, also, a pinion I³, which, through idlers I⁴ I⁴ and pinion I⁵ on shaft I', communicate motion to the shaft I'. Hence by turning shaft I all four wedge-slides are simultaneously operated, and correspondingly all four vertical rolls c c c' c' are adjusted toward or from the central line of the mill exactly the same distance. This adjustment of the rolls and the mechanism for obtaining it I consider very important features of my mill.

It is essential to have all four rolls move exactly alike and by means readily controllable. The wedge-slides G and connections accomplish this, and when the rolls are once adjusted they cannot be forced back or the wedge-slides moved by any pressure against their beveled surfaces, the rolls being thus practically locked in their places. When the wedge-slides G are raised, the rolls c c c' c' are free to move outwardly, and are so moved by the ingot passing through between them until further movement is arrested by the wedge-slides.

The appliances so far described constitute one complete part of the mill and have a definite work to perform. The first pass of the ingot, forged to such shape and dimensions as to pass into the bite of the rolls, is made through this part of the mill, and the first reduction of the web of the beam takes place under the action of the collars of the horizontal rolls C C'. At the same time the edges of the beam-flanges are rolled by the narrow portions of the horizontal rolls and the width of the beam determined by the vertical rolls c c c' c', which, however, do not necessarily roll the metal, being out of such operative position. They tend, however, to prevent undue lateral

spreading of the metal under the squeeze of the horizontal rolls C C' and the bending outward of the flanges without the rubbing or tearing effect produced by the outer surfaces 5 of the grooves in grooved horizontal rolls.

The web of the beam is reduced in this pass, and at the same time and by the same horizontal rolls the flanges are rolled to a uniform depth and the channel of the beam accurately shaped to conform to the shape of the collar of the horizontal roll. After this pass the beam is in condition for a pass through 10 the second section of the mill. This section, of which the housings B B are a part, is situated any convenient distance back of the first section, so that the beam leaving the first pair of rolls enters the second pair.

The latter consist of the shafts D D' and the central disk or collar portions D² D³, the 20 latter being of the exact width of the channel-spaces in the beams between the flanges—that is, of exactly the same width as the collars on the first pair of rolls. The disks or collars D² D³ are, however, of exceptionally- 25 large diameter, so as to leave ample space between the shafts D D' for the accommodation of the vertical rolls M M and their fittings between the shafts and on line with the vertical centers of the shafts D D'.

30 While in the first section of the mill the two horizontal rolls are worked positively from the power and their shafts gear together the lower roll D' only of the second section is positively rotated from the power, the upper roll being turned by the friction of the beam. The vertical rolls in this section of the mill do the positive rolling, while the horizontal rolls prevent the web from buckling and maintain the flanges from inward bending or crushing.

40 The vertical rolls are M M and are mounted in U-bearings N N, which slide in frames n n, secured on the housings B B.

The bearing-pieces N N are beveled on 45 their rear sides, and against the latter press the beveled portions n² n³ of the horizontal wedge-bars O O, which pass through mortises P P in the housings B B from front to rear. The frames n n are secured in any desired manner, but preferably, as shown, between 50 the journal-boxes and upon brackets in the window of the housing of the horizontal rolls, the frames n n having shoulders n³ n³, which abut against the inner sides of the housings B B, so as to sustain lateral pressure.

55 The wedge-slides O O are somewhat like the wedge-slides G, by which the vertical rolls c c c' c' are adjusted, but have each but one beveled face n², the slide being of full thickness for one-half its length and being then 60 beveled and diminished to half this thickness, the mortises in the housings being of corresponding widths, so that the slides will move lengthwise only and without any lateral play.

The thinner portions of the wedge-slides O 65 O extend outward from the housings toward the housings A A and are formed with racks P⁴ P⁴ on their upper edges, with which pin-

ions P² P² engage to move the slides in and out, such pinions being mounted on a transverse shaft p, journaled in boxes P², attached 70 to the housings and provided with a crank P³.

The vertical rolls M M are adjusted toward the rolls D² D³ by the inward movement of the wedge-slides and are moved outwardly by the pressure of the beam. The rolls M M are 75 rotated positively from the shaft of the lower roll D³ by the beveled gears Q Q', the large gears Q being splined upon the shafts and provided with grooved collars q, with which the lower spindles of the vertical rolls engage, 80 so that the gears are kept in operative engagement while the vertical rolls are adjusted.

When the mill is in operation, the vertical rolls M M are rotated at about the same speed as the vertical rolls c c c' c', so that the ingot 85 emerging from the pass through the first section of the mill shall not be restrained or dragged. Power is conveyed to the rolls in any desired manner, and I have shown a convenient arrangement in which the shafts of 90 the lower rolls are gear-coupled through gears R R' on their respective shafts and an intermediate idle-gear S on a separate shaft. The usual mill arrangement of shafts and gearing is of course adopted, the shafts proper of 95 the rolls being unencumbered, the gearing being on outside shafts, which are coupled when necessary with the roll-shafts by suitable crabs.

It will be understood that the two sections 100 of the mill constitute two separate and independent mills, but in respect to their operations and alternate uses form a train, one section being fed from the other and each dependent upon the operation performed by the other.

As previously stated, the first pass of the 105 fresh unfinished ingot is made through the first section—that is, between the rolls C C' and c c c' c'.

As the reduced ingot, having its web and flanges uniformly rolled, emerges and enters the pass of the second section, which is widened or enlarged to admit the end of the beam, the upper roll D D² is lowered and the vertical rolls 110 M M are moved inwardly by turning the hand-wheels s on adjusting-screws S of the upper roll and the pinion-shaft p until the rolls touch and slightly grasp the ingot. The latter now passes from the first horizontal 115 rolls and through the second, whereupon a further inward adjustment of the rolls M M is made and the operation of the mill reversed. The ingot is now fed back through the pass of the rolls D D' M M and is positively operated on by the vertical rolls M M, which roll the outer sides of the flanges, 120 properly reducing and evening them, the form of the web and of the inner sides of the flanges being preserved and the bending, contraction, or buckling prevented by the enlargements D² D³ of the rolls D D'. As the rolls D D' are not called on to operate positively as reducing appliances and are not sub-

ject to any special strain, they need not be heavy in proportion to their diameter, but may be hollow or webbed. The ingot in passing from these rolls again enters the first pair, but in an opposite direction from that of the first pass, and as it enters the rolls C c c' c' are adjusted inwardly, so as to grasp the beam and the latter fed through. The mill is reversed, the rolls C c c' adjusted, if necessary, and the first pass repeated, the operations and alternate passes being repeated until the beam is finished.

As will be seen, at no period is the ingot subjected to any bending, buckling, or other restraint which would interfere with the proper working of the metal or its uniform reduction. It is free to adapt itself to the exact form of each pass and the pressure is in the direction of forcing the flanges into proper shape and dimensions and of insuring evenness and uniformity.

When it is desired to change the gage of the mill, the horizontal rolls are readily removed and others of different dimensions substituted, and to make a channel-bar a plain roll is put on top, the vertical rolls remaining the same.

The horizontal rolls, not being grooved, are more readily and accurately cut than grooved rolls and may be turned from chilled metal, thus rendering them more durable than unchilled metal.

Having described my invention, what I claim, and desire to secure by Letters Patent, is—

1. A compound or multiple universal rolling-mill comprising two sets of universal rolls, one set consisting of a pair of horizontal rolls and a pair of vertical rolls arranged out of alignment with the axis of the horizontal rolls, being constructed and adapted to roll and reduce the web and flanges of an L-beam or channel-bar in a vertical direction only, and the other set consisting of a pair of horizontal rolls and a pair of vertical rolls in alignment with the axis of the horizontal rolls, being constructed and adapted to roll the bar or beam in a lateral direction only, the vertical rolls of both sets being combined 50 with mechanism for positively driving them, substantially as described.

2. In a compound universal rolling-mill, the combination of two distinct sets of universal rolls arranged in proximity to each other and 55 with their respective passes in horizontal alignment, one set comprising horizontal rolls and laterally-adjustable vertical rolls out of axial alignment with the horizontal rolls and the other set comprising horizontal rolls and

laterally-adjustable vertical rolls in axial alignment therewith, substantially as described.

3. The method of rolling I-beams or channel-bars, which consists in first reducing the web and flanges by pressure normal to the plane 65 of the web, and, second, in simultaneously supporting the web and inner faces of the flanges and rolling the parallel outer faces of the flanges, substantially as described.

4. In universal mills for rolling I-beams or channel-bars, the combination, with horizontal rolls one of which has a central enlargement or collar to roll and reduce the web of a beam, of horizontally-adjustable vertical rolls mounted in sliding boxes, slotted guide-bars 75 supporting said boxes and provided each with two wedges, one at the top and the other at the bottom of the vertical roll, wedge-slides bearing upon said boxes, and means for moving all said wedge-slides and thereby adjusting said vertical rolls simultaneously, substantially as described.

5. In universal mills for rolling I-beams or channel-bars, the combination, with the horizontal rolls constructed and adapted to roll 85 the web and flanges of an I-beam or channel-bar, of the laterally-adjustable vertical rolls arranged out of alignment with the horizontal rolls, the journal-boxes and supporting-bars of said vertical rolls, the wedge-slides impinging against said boxes, the pinions engaging with racks on said wedge-slides, the pinion-shafts supporting said pinions, and the gearing coupled to said shafts, through which the slides are moved and the vertical rolls there- 95 by adjusted, substantially as described.

6. In rolls for rolling I-beams or channel-bars, the combination, of the horizontal rolls, a sliding pinion on the shaft of one of said horizontal rolls, a pair of vertical rolls located 100 between the shafts of the horizontal rolls, pinions on the shafts of the vertical rolls engaging with said sliding pinions, sliding bearings in which said vertical rolls are mounted, having beveled rear faces, frames mounted 105 on the housings in which said bearing-pieces slide, and wedge-slides passing through the housings in the rear of the bearing-slides, with racks formed on their upper edges and pinions engaging with said racks, substan- 110 tially as described.

In testimony that I claim the foregoing I have hereunto set my hand this 25th day of September, 1891.

ABRAM REESE.
